VISIBLE INDEX

Filed June 15, 1928

UNITED STATES PATENT OFFICE

ALWIN VON AUW, OF BROOKLYN, NEW YORK, ASSIGNOR TO BOORUM & PEASE COMPANY,
OF BROOKLYN, NEW YORK, A CORPORATION OF NEW YORK

VISIBLE INDEX

Application filed June 15, 1928. Serial No. 285,581.

This invention relates to the overlapping type of visible index card having a hinged slideable mounting and is in the nature of an improvement upon cards having ears outside the body of the card at either side and parallel to those sides.

10 Heretofore, I have found it advantageous to give to the lower tip of the depending ear in the process of manufacture a permanent dorsal bend in order to aid the accurate interengagement between the cards when a new card is being added to a column in a panel, for example.

15 One object of this invention is to provide a depending ear card, in which the lower tip of the ear may be normally depressed without the necessity of permanently depressing the ear during the process of manufacture.

Another object is to provide an index card
20 in which the ears are protected against accidental injury or removal. Other objects will appear as the cards are described.

In the drawings:—

Figure 1 is a plan view of a number of
25 cards made according to my invention and
mounted upon a panel;

Figure 2 is a portion of a plan view of a card made according to my invention, broken to show a detail;

30 Figures 3 and 4 are views similar to Figure 2 showing modifications; and

Figure 5 is an end view looking from right to left of the upper portion of a card such as shown in Figures 2, 3 or 4.

35 The cards of my invention are of the general type shown in my Patent No. 1,649,763, Nov. 15, 1927, and application Ser. No. 278,587, filed May 17, 1928, in which the cards 12 are hinged at 15 and are provided
40 adjacent their upper edge 19 with lateral depending ears 14, severed from the body of the cards up to the point 16, which is the topmost point of each free side edge of the cards and is below the top edge of the card
45 and at or slightly above the hinge line 15.

I have found that the dorsal bend, which insures the straddle between adjacent cards, may be given to the tip 35 of the ear by securing the reinforcing strip 20 across the top 50 of the rear of the card. The strip 20 extends

from the lateral edge 22 of one ear to the lateral edge 23 of the other ear, and from the top edge 19 of the card to a point 21 below the hinge 15 but above the tip of the ear 35. The strip is slit along the line of severance of the ear from the body of the card 12, up to the point of severance 16. Thus the ear, except for the tip 35, is covered by the reinforcing strip 20, and the hinge line 15 is also covered by the strip 20. I make the strip 20 of flexible, tough material such as linen, muslin or the like. I make the body and ears of the card of sheet material such as paper, cardboard or any suitable material.

In the process of manufacture the tip 35 of the ear may be pressed to lie dorsal to the body 12 of the card, as shown in Fig. 5. But even if this step is not included in manufacturing my improved card, in the process of use after the card has been inserted once or twice upon a panel 10, for example, it will acquire and permanently retain the dorsally depressed tip 35 shown in Fig. 5. This is due to the relative thinness of the tip 35 as compared with the otherwise reinforced ear 14, and to the definite crease line afforded by the bottom line 21 of the reinforcement. 65 70 75

When a new card is added to the panel 10, the body of that card lies over the bodies of the cards below it in the panel, but the ear 14 of the card being added is inserted under the flange 11 and also under the corresponding ears 14 of the cards already in the panel. The relatively thick portion of the ear reinforced by the strip 20, will press at 21 against the ears above it and the relatively thin tip 35 will be bent down at 21 by the pressure of the ears and the flange above it.

The reinforcing strip 20 also improves my card in that it strengthens the upper part of the card and of the ears by which the card is supported and spaced in the panel. There is much strain at the line where the ear 14 joins the body of the card, that is from 16, the point of severance of ear and body, to the top edge 19 of the card, with the result that heretofore the ears 14 have frequently been torn from the cards. The ears were also apt to become crumpled in use, and the cards were apt tear apart at the hinge line. In my im- 10

proved reinforced card the liability to tearing or crumpling is greatly reduced.

The preferred form of my improved card is that shown in Figs. 1 and 2 in which there is cut in the card at the hinge line a long slot 15^a extending almost but not quite to the point of severance 16. While the dimensions of the slot and the distance between its end and the point 16 are optional, I have found it useful to make the slot about one sixteenth of an inch wide, and to have it terminate about one fourth of an inch from the free side edge of the body of the card. Having the slot of such a substantial width gives a marked degree of hinge protection. That is to say, for the length of the slot the bending all occurs on the reinforcing strip rather than on the paper or other material of which the body of the card 12 is composed. This will lessen the liability of the paper of the card to become detached or peel away from the strip 20 at the upper and lower edges of the slot. Furthermore, by having a slot of this substantial width, the hinging or bending will not always occur at the same point, and the life of the hinge and therefore of the card will be lengthened.

By keeping the one-fourth inch of the body of the card at each end of the slot 15^a the card is strengthened at its point of greatest strain, that is at the juncture between the ear and the body of the card. However, I sometimes make my cards with the slot 15^b running from ear to ear, as shown in Fig. 3. If preferred, the cards may also be made with a series of short slots 15^c as shown in Fig. 4. Other variations of details within my invention will occur to those skilled in the art.

I claim:

- 40 1. A visible index card comprising a body portion and a depending ear at either side of said body portion adjacent the upper edge, said body portion being hinged on a line reaching from one free side edge of said body portion to the other, and a reinforcing strip across the top of the rear of said card and covering each ear, except the lower tip thereof.
- 50 2. A visible index card comprising a body portion and a depending ear at either side of said body portion adjacent the upper edge, said body portion being hinged on a line reaching from one free side edge of said body portion to the other near the top, and a reinforcing strip on said card covering the hinge line.
- 60 3. A visible index card comprising a body portion and a depending ear at either side of said body portion adjacent the upper edge, said body portion being hinged on a line reaching from one free side edge of said body portion to the other, and a reinforcing strip across the top of the rear of said card and covering the ears, except the lower tips there-

of, the lower tips of said ears being bent at an angle dorsal to the body of the card.

4. A visible index card comprising a body portion and a depending ear at either side of said body portion adjacent the upper edge, 70 said body portion being hinged on a line reaching from one free side edge of said body portion to the other, and a reinforcing strip covering the rear of each ear except the lower tip thereof, and giving the main portions of said ear a materially greater thickness than said tip.

5. A visible index card comprising a body portion and a depending ear at either side of said body portion adjacent the upper edge, 80 said body portion being hinged on a line reaching from one free side edge of said body portion to the other, said ears being reinforced substantially as described.

6. A visible index card comprising a body portion and a depending ear at either side of said body portion adjacent the upper edge, 85 said body portion being hinged on a line reaching from one free side edge of said body portion to the other, said card being reinforced substantially as described.

7. A visible index card including a body portion and suspending and spacing means outside said body portion comprising a depending ear joined thereto on each side adjacent the upper edge thereof, and severed from each free side edge of the body portion to a point below the top edge of the card, said body portion being hinged on the line joining said points, in combination with a reinforcing strip across the top of the rear of the card covering the hinge line and lying on both sides thereof, the body of the card being cut away along the hinge line almost but not quite to the said limiting points of severance between the body of the cards and the ears.

8. A visible index card including a body portion and suspending and spacing means outside said body portion comprising a depending ear joined thereto on each side adjacent the upper edge thereof and severed from each free side edge of the body portion to a point below the top edge of the card, said body portion being hinged on the line 100 joining said points, in combination with a reinforcing strip across the top of the rear of the card covering the hinge line and lying on both sides thereof, the body of the card being cut away along the hinge line almost but not quite to the said limiting points of 105 severance between the body of the cards and the ears, and the reinforcing strip extending to the lateral edges of said ears and spaced above the lower tips of said ears.

9. A visible index card including a body portion and suspending and spacing means outside said body portion comprising a depending ear joined thereto on each side adjacent the upper edge thereof and severed from 110

- each free side edge of the body portion to a point below the top edge of the card, said body portion being hinged on the line joining said points, in combination with a reinforcing strip across the top of the rear of the card covering the hinge line and lying on both sides thereof, the body of the card being cut away along the hinge line almost but not quite to the said limiting points of severance between the body of the card and the ears, and the reinforcing strip extending to the lateral edges of said ears and spaced above the lower tip of said ears, said ears being creased at the lower edge of the strip so that the lower tips of the ears are bent at an angle dorsal to the body of the card. 5 70
10. A visible index card comprising a body portion and a depending ear at either side of said body portion adjacent the upper edge, said body portion being hinged on a line reaching from one free side edge of said body portion to the other, and a reinforcing strip on the rear of the card covering the hinge line and lying on both sides thereof and extending to the lateral edges of the ears, the lower edge of said strip being spaced above the lower tip of said ears. 20 80
11. A visible index card comprising a body portion and a depending ear at either side of said body portion adjacent the upper edge, said body portion being hinged on a line reaching from one free side edge of said body portion to the other, and a reinforcing strip on the rear of the card covering the hinge line and lying on both sides thereof and extending to the lateral edges of the ears, the lower edge of said strip being spaced above the lower tip of said ears, and the lower tip of said ears being bent at an angle dorsal to the body of the card. 30 90
12. A visible index card made of one integral piece of sheet material comprising a body portion and a depending ear on either side of said body portion adjacent the upper edge, said ears being separated from the body portion below the junction between said body portion and said ears, in combination with a reinforcing strip covering the rear of each ear except the lower tip thereof. 40 100
13. A visible index comprising a panel having inwardly facing opposed flanges in combination with a series of overlapping hinged cards each comprising a body portion overlying the body portion of the card below and a depending ear attached to each side of the body portion adjacent its upper edge underlying the corresponding flange and the ear of the card below, and a reinforcing strip along the top of the rear of each card covering each ear except the lower tip thereof. 50 110
14. A visible index comprising a panel having inwardly facing opposed flanges in combination with a series of overlapping hinged cards each comprising a body portion overlying the body portion of the card below 60 120
- and a depending ear attached to each side of the body portion adjacent its upper edge underlying the corresponding flange and the ear of the card below, and a reinforcing strip on the card covering the hinge line and lying on both sides thereof and extending to the lateral edges of the ears. 70 125
15. A visible index comprising a panel having inwardly facing opposed flanges in combination with a series of overlapping hinged cards each comprising a body portion overlying the body portion of the card below and a depending ear attached to each side of the body portion adjacent its upper edge underlying the corresponding flange and the ear of the card below and a reinforcing strip on the rear of the card covering the hinge line and lying on both sides thereof and extending to the lateral edges of the ears, the lower edge of said strip being spaced above the lower tip of said ears. 75 85
16. A visible index comprising a panel having inwardly facing opposed flanges in combination with a series of overlapping hinged cards each comprising a body portion overlying the body portion of the card below and a depending ear attached to each side of the body portion adjacent its upper edge underlying the corresponding flange and the ear of the card below and a reinforcing strip on the rear of the card covering the hinge line and lying on both sides thereof and extending to the lateral edges of the ears, the lower edge of said strip being spaced above the lower tip of said ears, the body of the card being cut away along the hinge line almost but not quite to the points of severance between the body of the card and the ears. 90 100
17. A visible index card comprising a body portion and a depending ear at either side of said body portion adjacent the upper edge, said body portion being hinged on a line reaching from one free side edge of said body portion to the other, and a reinforcing strip covering the rear upper part of each ear and the portions of the card surrounding the point of severance between the ear and the body of the card. 105 110
- In testimony whereof I have signed my name to this specification. 115

CERTIFICATE OF CORRECTION.

Patent No. 1,765,193.

Granted June 17, 1930, to

ALWIN VON AUW.

It is hereby certified that error appears in the printed specification of the above numbered patent requiring correction as follows: Page 1, line 55, after the sentence ending "ear 55." insert "Making the reinforcement one continuous strip extending from lateral edge to lateral edge of the card is optional."; same page, line 100, after "apt" insert "to"; and that the said Letters Patent should be read with these corrections therein that the same may conform to the record of the case in the Patent Office.

Signed and sealed this 22nd day of July, A. D. 1930.

(Seal)

**Wm. A. Kinnan,
Acting Commissioner of Patents.**
